UNITED STATES PATENT OFFICE.

JOSEPH HACKETT, OF LOUISVILLE, KENTUCKY.

DESIGN FOR AN OPEN-GRADE STOVE.

Specification forming part of Design No. 5,758, dated April 9, 1872.

Specification describing a new and original Design for a Stove, invented by JOSEPH HACKETT, of Louisville, in the county of Jefferson and State of Kentucky.

Similar letters of reference indicate corresponding parts.

This invention relates to a new outline for a stove; also to a new ornamentation of the same. The ornamentation of the stove by the various rows of beads, its panels and moldings, is clearly represented in the photographic illustration. The invention also consists in a new ornamentation of the blower by means of radial and peripheric ribs, as shown.

I claim as my invention—

1. The design for the configuration of a stove, as shown and set forth.
2. The design for the ornamentation of a stove, as shown.
3. The design for the ornamentation of a blower, as shown.

JOSEPH HACKETT.
